United States Patent Office

Des. 195,021
Patented Apr. 16, 1963

195,021

NECKTIE

Arthur N. Weeks, 12338 Montana, Los Angeles, Calif.

Filed June 18, 1962, Ser. No. 70,587

Term of patent 7 years

(Cl. D3—16)

I claim:

The ornamental design for a necktie, substantially as shown.
